HEEL SUPPORT FOR BACKLESS SLIPPERS

Michael Vardy, New York, N. Y.

Application May 8, 1940, Serial No. 333,923

2 Claims. (Cl. 36—53.5)

This invention relates to new and useful improvements in a heel support for backless slippers.

More specifically, the invention proposes the construction of a heel support for backless slippers characterized by a low counter portion mounted along the heel portion of a slipper proper for engaging about the very bottom portion of the heel of one's foot to conceal the lower portion of the seam of one's stocking and to provide a better support for the foot.

Still further it is proposed to provide the low counter portion with a crescent shaped lining of resilient material adapted to frictionally engage the bottom of the heel of one's foot to more securely hold the slipper in position thereon.

Still further it is proposed to characterize the crescent shaped lining by a piece of elastic material having its top edge securely attached to the counter portion and its bottom edge projected towards the inside of the slipper in a manner to engage the said heel as hereinbefore outlined.

Still further the invention proposes the construction of a means for holding the front ends of the crescent shaped lining in various forward projected positions for increasing the grip of the lining on the foot.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a backless slipper constructed in accordance with this invention.

Fig. 2 is a plan view of Fig. 1.

Fig. 3 is a partial vertical sectional view on the line 3—3 of Fig. 2.

Fig. 4 is an enlarged detailed view similar to a portion of Fig. 1 but illustrating a modification of the invention.

Fig. 5 is a perspective view of another heel portion constructed in accordance with this invention.

The heel support for backless slippers, according to this invention, is adapted to be applied to a backless slipper 10. This backless slipper 10 has a sole portion 10^a, and a heel portion 10^b. A vamp 10^c is mounted upon the forward portion of the sole 10^a and is adapted to receive and encase the front portion of the foot. A strap 10^d is provided for encircling the ankle and is provided

5 with a pair of downwardly extending oppositely disposed strips 10^e which are attached to the sole portion 10^a in the vicinity of the shank area. This strap 10^d is formed with an open side closed by means of a buckle 11 for permitting the same to be conveniently engaged about one's ankle.

The heel support comprises a low counter portion 12 mounted upon the rear portion of the slipper proper and adapted to engage the bottom of the heel of one's foot. This counter portion 12 is preferably constructed of leather and is provided for concealing the lower end of the seam of the stocking and for holding the rear portion of the foot in an aligned position with the sole 10^a thereof.

10 The low counter portion is provided with an internal means for frictionally gripping the lower portion of one's heel for preventing said heel from sliding in and out of the counter portion. This means comprises a crescent shaped lining 13 mounted on the inside of the counter portion 12. This crescent shaped lining 13 is preferably formed of elastic or rubber material and has its top edge stretched and securely attached to the top edge of the counter portion 12 by means of a line of stitches 14. This stretching of the top edge of the crescent shaped lining 13 causes the bottom edge thereof to be spaced from the adjacent face of the counter portion, as shown in Fig. 3, for causing the same to tightly engage about and grip one's heel when engaged in position within the counter portion 12.

15 According to the modification of the invention shown in Fig. 4 the construction of the heel support for a backless slipper is similar to that previously described except that the crescent shaped lining 13' has only the intermediate portion of its top edge stretched and securely attached to the adjacent face of the counter portion 12 by means of 20 a short line of stitches 14'. The ends of the crescent shaped lining 13' are free of the counter portion 12, and means is provided for releasably attaching the front ends of the lining 13' in various forward positions with relation to the counter portion for increasing the grip of the lining on the lower portion of the heel of one's foot.

25 This latter means comprises a snap fastener element 15 mounted upon each of the ends of the lining 13' and which are adapted to be selectively engaged with one of a plurality of complementary snap fastener elements 16 mounted on the inside face of the front ends of the counter portion 12. It is preferred that the snap fastener elements 16 be the female parts thereof for forming a flat interior which is adapted to engage

against the heel of one's foot when these snap fastener elements 16 are exposed.

In other respects this form of the invention is similar to the previous form and like parts may be identified by like reference numerals.

In Fig. 5 the counter portion 12' is shown to be separated from the slipper. In this form of the invention, apertures 17 are shown through which nails or the like may be driven into the sole portion 10a, to keep the counter portion 12' on the slipper. The counter portion 12 and 12' may be made of any material suitable for the purpose of supporting the heel of the foot, as previously described.

It is to be understood that the heel support may be ornamented or shaped as desired and it may be equipped on any slipper or shoe, worn by women, children or men.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a backless slipper having a very low counter portion for engaging about the base of one's heel, a crescent shaped lining of elastic material having the central portion of its top edge

stretched, said stretched central top edge portion being attached to the top edge of said counter portion leaving the ends and bottom edge of said lining free to engage frictionally about the base of the back of one's heel to hold the heel of said slipper in position thereon, and means for holding the bottom edge of said lining in various forward projected positions to increase the frictional engagement of said bottom edge against the base of the back of one's heel.

2. In a backless slipper having a very low counter portion for engaging about the base of one's heel, a crescent shaped lining of elastic material having the central portion of its top edge stretched, said stretched central top edge portion being attached to the top edge of said counter portion leaving the ends and bottom edge of said lining free to engage frictionally about the base of the back of one's heel to hold the heel of said slipper in position thereon, and means for holding the bottom edge of said lining in various forward projected positions to increase the frictional engagement of said bottom edge against the base of the back of one's heel, comprising fastening elements mounted on the ends of said lining adjacent the bottom edge thereof and selectively engageable with one of a plurality of complementary fastening elements mounted on the inside face of said counter portion adjacent the ends of said lining.

MICHAEL VARDY.
